US00D755847S

(12) **United States Design Patent**
Butcher et al.

(10) **Patent No.:** **US D755,847 S**
(45) **Date of Patent:** **** May 10, 2016**

(54) **DISPLAY SCREEN OR PORTION THEREOF
WITH GRAPHICAL USER INTERFACE**

(71) Applicant: **Microsoft Corporation**, Redmond, WA (US)

(72) Inventors: **Larry Russell Butcher**, Seattle, WA (US); **Amish Patel**, Seattle, WA (US)

(73) Assignee: **Microsoft Corporation**, Redmond, WA (US)

(**) Term: **14 Years**

(21) Appl. No.: **29/492,502**

(22) Filed: **May 30, 2014**

(51) **LOC (10) Cl.** **14-04**

(52) **U.S. Cl.**
USPC **D14/492**

(58) **Field of Classification Search**

USPC D14/485-495; D5/4-9, 16, 20-22, 41

CPC G06F 3/04817

See application file for complete search history.
